Patented Nov. 27, 1956

179,331

CHAMPAGNE BOTTLE STOPPER

Floyd A. Terwilliger, Rochester, N. Y.

Application January 13, 1956, Serial No. 39,745

Term of patent 14 years

(Cl. D58—26)

FIG. 1.

FIG. 2.

FIG. 3.

FIG. 4.

Fig. 1 is a side elevation of a champagne bottle stopper embodying my new design;

Fig. 2 is an axial section therethrough;

Fig. 3 is a top plan view thereof; and

Fig. 4 is a bottom view thereof.

I claim:

The ornamental design for a champagne bottle stopper, substantially as shown.
